LUCIUS N. DIEHM, OF WEST HARTFORD, CONNECTICUT, ASSIGNOR OF ONE-HALF TO
BERKLEY C. STONE, OF MIDDLETOWN, CONNECTICUT.

FIREARM.

1,187,888.

Specification of Letters Patent. Patented June 20, 1916.

Application filed July 23, 1913. Serial No. 780,711.

To all whom it may concern:

Be it known that I, LUCIUS N. DIEHM, a citizen of the United States, and a resident of West Hartford, in the county of Hartford and State of Connecticut, have invented a new and Improved Firearm, of which the following is a specification.

My invention relates more especially to that class of firearms commonly designated by the term "automatic," and an object of my invention, among others, is to provide a firearm of this class, extremely simple in construction, and rapid and effective in operation.

15 One form of device embodying my invention, and in the construction and use of which the objects herein set out, as well as others, may be attained, is illustrated in the accompanying drawings, in which—

20 Figure 1 is a view, in central longitudinal section, of a pistol embodying my invention. Fig. 2 is a side view of the same, partially broken away and with parts removed. Fig. 3 is a view in longitudinal section through 25 the center of the barrel of a pistol embodying my invention, looking downward.

My invention is applicable to firearms of various forms and construction, but for the purpose of disclosure of my invention herein, I have selected a pistol, that is, a firearm adapted to be held in one hand when discharged, in which the invention is embodied, and in the accompanying drawings the numeral 6 indicates the frame of the pistol, 35 that is preferably formed of a single piece of material, as metal, which frame includes a handle 7, trigger guard 8, and receiver 9, the latter constituting the entire upper part of the frame that is provided with a breech bolt opening 10, extending laterally through it, and a barrel receiving opening 11 extending from the breech bolt opening to the front of the receiver part of the frame. The wall of this opening 11 is threaded for 40 the reception of a barrel 12, the latter having a shoulder 13 resting against the end of the receiver part of the frame. In the form of construction herein shown the wall of the opening 11 is threaded for a portion of its length only from its front end, and the barrel is correspondingly threaded, its extreme inner end being smooth and nicely fitting the smooth portion 14 of the opening 11. The inner end of the opening 11 through the barrel is formed into a cartridge

receiving chamber 15 for the reception of cartridges 16.

A magazine opening 17 is formed lengthwise through the handle 7, this opening extending from the lower end of the handle upward into the breech bolt opening 10, and being adapted to receive a magazine 18 of any ordinary form and construction, to hold the cartridges 16, the latter being fed upward in a manner common to magazines of this class and which will be readily understood by those skilled in the art, and for which reason further illustration and description is omitted herein.

A breech bolt 19 is located to slide in the breech bolt opening 10, this breech bolt having side parts 20, preferably extending beyond the rear end of the breech bolt to close the opening 10 when the breech bolt is at the forward limit of its sliding movement. The side parts also have flanges 21 at their upper and lower edges to retain the breech bolt in place and guide it in its sliding movement. This breech bolt may embody various forms of construction, as shown herein a side part, including a rearward extension and the flanges 21 on one side of the bolt, being formed integrally therewith while the side part on the opposite side of the breech bolt is formed separately therefrom and is removably secured thereto in any suitable manner. In the structure illustrated this removable side part has dove-tail shaped edges fitting a dove-tail shaped groove in the side of the breech bolt, and a pin 22 seated upon a spring 23 in a recess in the side of the breech bolt forces the retaining pin 22 normally outward into a holding recess 24 extending from the inner surface of the side part, a releasing opening 25 extending from the holding recess to the outer surface of the side part, into which releasing opening an instrument may be inserted to press the pin inward and release the side part. Each of the side parts is preferably provided with a roughened surface 26 as an aid in the manual operation of the breech bolt. A cartridge receiving recess 27 is formed in the front end of the breech bolt, a cartridge inserting lip 28 being formed on one side of the recess 27, and on the lower side of the breech bolt, and by means of which the cartridges are thrust into the cartridge receiving chamber 15 in the barrel. A firing pin 29 is fixed in

the breech bolt, projecting into the recess 27 in position to strike the primer in the end of the cartridge.

An actuating spring chamber 30 is formed 5 in the breech bolt for the reception of an actuating spring 31, one end of which thrusts against the bottom of said chamber and the other end of which is located in a recess 32 formed in the receiver part of the frame 10 and extending backward from and opening out of the breech bolt opening 10. The chamber 30 and recess 32 are preferably located at one side of the longitudinal center of the frame, and an ejector pin 33 is located 15 within the spring 31, the latter seating against a head 34 on the ejector pin, and this head fits snugly within the recess 32 to position the ejector and insure the entrance of its opposite reduced end within a hole 20 35 in the breech bolt. This pin 33 is of such length that it will project through the breech bolt and into the recess 27 when the breech bolt is at the backward limit of its play.

A sear opening 36 extends from the under side of the projecting rear part of the frame into the breech bolt opening 10, this sear opening being closed by a filling piece 37, removably secured in place in any desired manner. A sear spring 38 is secured 30 to the filling piece, which spring acts against a sear 39 pivotally mounted in the sear opening 36. One end of the sear is adapted to engage in a notch 40 in the underside of the breech bolt, and the other end of the sear 35 is adapted to engage the teeth of a sear actuator 41. This sear actuator forms an important part of my invention and it and the sear are so constructed that the release of the breech bolt from the sear and the sear 40 from the actuator take place almost simultaneously so that, no matter how quick the action of the breech bolt, the sear is always in position to catch within the notch 40. In the form of sear actuator shown herein it 45 consists of a toothed wheel pivotally mounted within the sear chamber, the teeth being adapted to move the sear to disengage it from the notch 40 in the breech bolt. A sear actuating bar 42 is located in a sear 50 actuating bar recess 43 in the side of the frame, one end of this bar having a hook 44 arranged to engage the teeth on the sear actuator, and the other end of the bar being pivotally connected to an extension 45 from a trigger 46 pivotally mounted in the frame 55 in the ordinary manner of such devices. A plunger 47 thrusts against the extension 45 under the force of a spring 48, the plunger and spring being located in a recess in 60 the frame which recess is closed by a screw cap 49. A plate 50 is employed to cover the sear actuating bar recess 43, and side plates 51 to cover the opening in the handle part of the frame. A spring actuated catch 52 is 65 arranged to engage the end of the magazine

to retain it in place, this catch being actuated as by means of a button 53.

It will be noted that the forces of the moving parts due to the action of the gases of explosion are opposed by solid abutments, 70 that is, the entire frame is formed of a single piece, without joints, and these forces are exerted upon this solid frame. It will be further noted that the breech bolt serves the double function of a breech bolt and a hammer, and that the breech bolt in its forward movement forces the cartridge into the receiving chamber 15 and in the same movement projects the pin 29 against the primer to explode the cartridge, and this structure 80 together with the connection between the trigger and the breech bolt is thus reduced to a minimum number of parts of the simplest construction.

In the operation of the device, the parts 85 being in the position shown in Fig. 1, a pull upon the trigger 46 moves the bar 42, the engagement of the end of which with the actuator 41 rotates the latter, operating the sear and disengaging it from the breech bolt. 90 The latter is forced forward by the action of the spring 31 carrying with it a cartridge and inserting the latter into the chamber 15, the cartridge thus alining itself with the recess 27. Promptly upon placement of the 95 cartridge the pin 29 strikes the primer and explodes the cartridge. The expansion of the gases of explosion forces the bullet out through the barrel and at the same time forces the shell of the cartridge backward in 100 a manner that will be readily understood by those skilled in the art. This force of the backward movement of the cartridge shell carries the breech bolt with it, against the resistance of the spring 31, and the sear, 105 which was promptly released from the sear actuator, will always be in position to engage the notch 40 and retain the breech bolt in its backward position, ready for the operation to be repeated.

It will be noted that the firearm cannot be accidentally discharged for the reason that only at the instant of firing is there a cartridge in place to be discharged. By releasing the catch 52 and moving the magazine downward a slight distance the breech bolt may be moved to the forward limit of its play and the magazine returned to place. This will be the normal position of the parts when the firearm is not in use. When it is 120 desired to use it the breech bolt may be manually moved backward by pressure applied by the thumb and finger upon the side parts 20.

While I have illustrated and described 125 herein a preferred arrangement of parts embodying my invention, this construction may be departed from to a greater or lesser degree and yet be within the spirit and intent of the invention.

I claim:—

1. A firearm including a frame formed of a single piece of metal with an opening laterally therethrough constituting a breech-bolt chamber, a breech-bolt located in said chamber for longitudinal movement therein, means for preventing lateral movement of the breech-bolt, said means including a side part, and means for removably securing the side part to the breech-bolt.
2. A firearm including a frame formed of a single piece of metal with an opening laterally therethrough constituting a breech-bolt chamber, a breech-bolt located in said chamber and having flanges on one side projecting beyond its edges, and a side part removably secured to the opposite side of the breech-bolt and projecting beyond its edges forming flanges to retain the breech-bolt in place.
3. A firearm including a frame formed of a single piece of metal with an opening laterally therethrough constituting a breech-bolt chamber, a breech-bolt located in said chamber and having side parts extending beyond its edges to hold the breech-bolt in place, said side parts also extending beyond the back end to an extent to cover the breech-bolt chamber when the breech-bolt is at the forward limit of its play, and means for permitting removal of one of said side parts to permit removal of the breech-bolt laterally from said chamber.
4. A firearm including a frame formed of a single piece of metal with an opening laterally therethrough constituting a breech-bolt chamber, a breech-bolt located in said chamber and having an integral flange on one side to retain the breech-bolt in place, a side part fitting a lipped groove in the opposite side of the breech-bolt, and overlapping the opening and means for removably holding the side part in place.
5. A firearm including a frame formed of a single piece of metal with an opening laterally therethrough constituting a breech-bolt chamber, a breech-bolt located in said chamber and having on one side an integral flange for preventing removal of the bolt, the opposite side of the bolt projecting beyond the side part of the frame and having a lipped longitudinal groove, a side part projecting into said groove, and a spring seated pin located in the bolt in position to engage a recess on the inner surface of the side part to hold it against movement.
6. A firearm including a frame having a breech-bolt chamber therein, a breech-bolt movably mounted in said chamber, a retaining member for holding the breech-bolt against forward movement, a ratchet rotatably mounted in the frame for engagement by said retaining member, an actuating bar projecting through the frame and having a toothed end to engage said ratchet, and a trigger pivotally connected with the actuating bar.
7. A firearm including a frame formed of a single piece of metal and having a breech-bolt chamber therein and a groove along the outer surface thereof, a recess extending laterally from one side into the frame, a breech-bolt movably located in the breech-bolt chamber, a ratchet located in said recess and extending to a point opposite said groove, a retaining member positioned to engage the ratchet and hold the breech-bolt from forward movement, an actuating bar located in said groove and having a tooth in engagement with the ratchet, and a trigger pivotally mounted in the frame and pivotally connected with said actuating bar.
